ENVELOPE MACHINE ATTACHMENT

Elijah G. Vallier, Wauwatosa, Wis., assignor to
Western States Envelope Company, Milwaukee,
Wis., a corporation of Wisconsin

Application April 2, 1942, Serial No. 437,377

8 Claims. (Cl. 93—61)

This invention relates to improvements in envelope machine attachments, and more particularly to an attachment for an envelope folding and gumming rotary machine, which attachment prevents the curling and cracking of the gummed flaps of envelope blanks.

In the envelope manufacturing industry, envelope folding and gumming rotary machines are in widespread use. Said machines operate on continuously supplied die cut flat envelope blanks. In one section of a rotary machine of the type under consideration, a succession of envelope blanks, having had gum applied to the top flaps thereof, are propelled by the lower extents of a conveyor along an apron overlying a heater, the latter being for the purpose of drying the gum on said flaps as the envelope blanks are moved rapidly therealong. Beyond the apron and heater the envelope blanks are propelled over an end rotary drum and along a top apron. Suitably positioned along the top apron and adjacent the conveyor chains moving thereover, are feeding segments which engage individual envelope blanks and rapidly propel the same toward subsequent instrumentalities which complete each envelope from the blank by applying gum to other flaps and by subsequently folding over certain of the blank flaps and causing the same to adhere. At the discharge end of the machine the completed envelopes are delivered in rapid succession for collection and packing.

It has been found that in rotary machines of the class under consideration, when the same are operating on blanks of certain types of stock of heavy paper or kraft, there is a tendency for the flaps which were initially gummed to curl and crack prior to reaching the feeding cams on the top side of the machine, with the result that those blanks having curled flaps (particularly at the ends) would be improperly engaged by the feeding cams and other instrumentalities, and hence the machine will ultimately discharge a series of defective envelopes, occasioned by undesired folds, curls, or creases in the pre-gummed flaps.

It should be observed that the tendency of the envelope blank gummed flaps to curl and crack is particularly pronounced and objectionable immediately after the machine has been stopped and then subsequently re-started. This results from the fact that during a stoppage of the machine a very substantial succession of blanks remain for an undue period on the lower apron over the heater, whereby this particular extent or succession of blanks has the gummed flaps

overheated and upon the re-starting of the machine, when the latter extent of blanks reach the top side of the machine ahead of the feeding cams, the ends and edges of the gummed flaps are in badly curled condition, so that the objections heretofore noted occur. It is, of course, then necessary for the operator of the machine to carefully note the envelopes discharged at the outlet end of the machine for a substantial period of time to remove the defective envelopes resulting from the curled and cracked flaps. Obviously during production operations, stoppages of the machine are periodically necessary for adjustments, etc. or for the insertion of blanks of a new type or size, and the discharging of a substantial batch of completed defective envelopes at the outlet end of the machine requires additional attention by the operator, slows down production, and hampers the efficiency and output of the machine.

With the above in mind it is, therefore, a general object of the present invention to provide an attachment for an envelope folding and gumming machine adjustably mountable on the upper extent of the conveyor ahead of the feeding cams and adapted to engage the gummed flaps of the successive envelope blanks for the purpose of flattening, smoothing, and de-curling the same so that they will be presented to the feeding segments and other subsequent instrumentalities in a flat condition, eliminating improperly curled and over-turned or rolled edges on the gummed flaps so that all of the envelopes discharged from the machine are perfectly formed and folded, whereby the efficiency and output of the machine is greatly enhanced.

A further object of the invention is to provide a flap de-curling attachment for envelope folding and gumming machines which is automatic in its operation and with which any standard envelope folding and gumming rotary machine may be readily equipped at a minimum of expense and with a minimum of modifications.

A further object of the invention is to provide a flap de-curler attachment for envelope folding and gumming machines having adjustable and interchangeable elements to adapt it to envelope blanks of any desired size.

A further object of the invention is to provide a flap de-curler attachment for envelope folding and gumming machines which is easily and quickly manipulatable from an operative to an inoperative position, the latter position permitting adjustments and interchangeability of parts.

A further object of the invention is to provide

in an envelope folding and gumming rotary machine an attachment to prevent flap curling and cracking, which attachment is of very simple construction, is strong and durable, is automatic and efficient in operation, and is well adapted for the purposes set forth.

With the above and other objects in view, the invention consists of the improved envelope machine attachment and its parts and combinations as set forth in the claims and all equivalents thereof.

In the accompanying drawings in which the same reference characters indicate the same parts in all of the views:

Fig. 1 is a fragmentary perspective view, with parts broken away and in section, of that portion of an envelope folding and gumming rotary machine with which the improved attachment is associated;

Fig. 2 is a fragmentary perspective view similar to Fig. 1 only showing the cradle attachment which carries the improved envelope flap pressure and breaker rolls swung to an inoperative position to permit adjustments or interchanging of parts;

Fig. 3 is a fragmentary plan view of the improved attachment and that portion of an envelope folding and gumming machine with which it is associated, parts being broken away and in section;

Fig. 4 is a longitudinal vertical sectional view taken on line 4-4 of Fig. 3;

Fig. 5 is a transverse vertical sectional view taken on line 5-5 of Fig. 3;

Fig. 6 is an enlarged transverse vertical sectional view through the improved attachment including the cradle, the pressure and breaker rolls, the upper apron or table, and the associated parts of an envelope folding and gumming machine;

Fig. 7 is a fragmentary detail view taken on line 7-7 of Fig. 3 and on a larger scale;

Fig. 8 is a fragmentary detail view similar to Fig. 7 only showing the parts in a different position of adjustment;

Fig. 9 is a fragmentary detail sectional view taken on line 9-9 of Fig. 3 only with releasable parts in a different position of adjustment, and on a larger scale; and

Fig. 10 is a fragmentary schematic view of that portion of an envelope folding and gumming rotary machine with which the present attachment is associated, and on a reduced scale.

Referring now more particularly to the drawings, it will appear that an envelope folding and gumming rotary machine is designated generally by the numeral 12. As shown schematically in Fig. 10 the machine includes a lower apron or table 13 along which flat envelope blanks 14 (see Figs. 1, 2 and 6) are conveyed by endless conveyor chains 15. The blanks have the top flaps 16 thereof gummed and are arranged in an overlapping succession with the gummed areas downwardly facing on the lower apron or table 13. Said apron is disposed over an elongated heater 17. Beyond the heater the succession of blanks is carried around a guide drum 18 and are then propelled by the conveyor chains along an upper apron 19. Positioned along the upper apron are instrumentalities for performing additional operations on the envelope blanks, including revoluble feeding members 20. The improved attachment, forming the principal subject matter of the present invention, is mounted adjacent the upper apron 19, in advance of the feeding members 20,

and is designated generally by the numeral 21. Its main function is to engage the upper surfaces of the advancing envelope blanks 14 and to flatten and de-curl the gummed flap portions 16 of said blanks, prior to engagement of the same by the feeding members 20. By virtue of the flattening and de-curling of said blank flaps 16 the same are subsequently properly engaged by the feeding members and subsequent instrumentalities, eliminating the possibility of undesired wrinkles, creases, or folds being formed in the same, whereby perfect completed envelopes may be discharged from the machine.

To carry and mount the improved attachment 21 a lower transverse frame bar 22 of the machine is formed with upstanding end brackets 23. Lower portions of said end brackets have rigidly secured thereto the reduced end portions of a transverse lower cradle 24. On an upper intermediate portion of the cradle, in spaced, longitudinal alignment, are a pair of revolubly mounted idler rollers 25 on which is revolubly seated an elongated transverse breaker roll 26 having its reduced end portions journaled in bearing lugs 27 on opposite end portions of the lower cradle 24.

The upper ends of the brackets 23 have integral slotted plates 28 (see Figs. 7 and 8). Within the slot of each plate is a vertically movable bearing block 29 in which is secured the end portion of an upper cradle shaft 30. An integral top bar 31 of a plate 28 has slidably extended therethrough a vertical rod 32 whose lower end is anchored to the block 29 and whose free upper end carries a flange 33 engaged by a cam 34 on the inner end of a turnably mounted horizontal stud 35. The outer end of the stud carries a manipulating handle 36. A coiled spring 37 is positioned on a portion of the rod 32, confined between the top of the block 29 and the bar 31, and normally exerts pressure on the block to maintain it in a lowered position in the slot of the plate 28.

Pivotedly mounted on the upper cradle shaft 30 is an upper cradle 38 in the form of an elongated boxlike enclosure having an open bottom, and closed side, end and top walls. The shaft 30 extends freely through openings in the end walls of said cradle so that said cradle may be turned or rocked on the shaft 30. Adjacent the outer face of each end wall of the cradle is an adjustable plate 39 whose upper edge is engaged by a turnable locking plate 40 which normally overlies an adjacent top portion of the cradle 38 and is secured thereto by a removable bolt 41. When the cradle 38 is in its normal, operative position, as in Fig. 4, spring urged movable legs 42 depending from the bottom edges of the end plates 39 are retracted under tension and yieldingly seat on horizontal flanges 43 on the lower cradle lugs 27.

Within the upper cradle 38 are a pair of adjustably spaced journal frames 44. Each has an upper flange underlying a slot 45 in the top wall of the cradle 38 and being adjustably held in a desired position by a headed clamping bolt 46 extending through the slot 45. The head of the clamping bolts may be brought into impingement with the stock adjacent the slots 45. The shaft 30 passes freely through openings in the ends of the frames 44 so that when the bolts 46 are loosened the frames may be adjusted longitudinally on the shaft 30. Longitudinal adjustments of the journal frames 44 are made when it is desired to remove or replace a pair of pres-

sure rolls 47. Each pressure roll 47 has reduced end shaft portions which are journaled in openings therefor in lower portions of the frames 44. The length of the pressure rolls 47 utilized is dependent upon the length of the flap portions 16 of the envelope blanks being operated on by the machine. If it is desired to substitute longer or shorter pressure rolls for those in the attachment, this change may be readily made, as will appear hereinafter. It should further be observed that a portion of the shaft 30 is formed with a longitudinal key 48, adapted to engage in a key-way 49 in a gear 50 longitudinally adjustably carried by an intermediate portion of the shaft 30. The shaft end portions of the interchangeable pressure rolls 47 have fast thereon gears 51 which are adapted to mesh with and to be driven by the gear 50 on the shaft 30 when said gear is in a proper position of longitudinal adjustment on said shaft.

Portions of the journal frames 44 have front and angled integral guide lugs 52 which longitudinally adjustably engage front wall portions of the upper cradle 38. Depending from these lugs are angular guide and flap flattening fingers 53 which project spacedly over the upper apron 19 in advance of the rolls 26 and 47 and serve to flatten the envelope blanks (particularly the end flap portions thereof) and to guide the same toward the rolls. As the fingers 53 are carried by the frames 44, they are adjustable therewith so as to be suitably spaced according to the lengths of the envelope blanks being operated on.

The conveyor chains 15 are continuously driven from a source of power (not shown) by means common in the type of machine under consideration. Likewise, from a convenient source of power extends a driving chain 54 engaging an idler sprocket 55 and extending about another sprocket 56. The latter sprocket, as well as a companion sprocket 57, is pinned to a common sleeve 58 revoluble on a reduced portion of the lower cradle end. An endless chain 59 drivingly connects sprocket 57 with another sprocket 60 fast on an end portion of the cradle shaft 30. The chain 59, however, additionally engages an idler sprocket 61 on the free end portion of a swingable arm 62 which functions to permit and to take up slack in the chain 59, slack in said chain being necessary when the cradle 38 is swung from the operative position of Fig. 1 to the inoperative position of Fig. 2, for replacements or adjustments. Normally an anchored spring 63 holds the arm 62 in a substantially upright position such as to keep the chain 59 taut, but said arm may be swung to the right (relative to Fig. 5), expanding said spring, when adjustments are made.

During normal operation of the improved envelope folding and gumming machine a plurality of flat die cut envelope blanks, having had gum applied to the top flap forming portions thereof, are propelled along the lower apron 13 and subsequently along the top apron 19, toward the instrumentalities which perform subsequent gumming and folding operations to the blanks to complete the same as envelopes. The blanks thus advanced are in an overlapping succession.

It frequently occurs, when the machine is operating on blanks of heavy stock, that the gummed flaps thereof will curl and crinkle before the blanks are delivered to the instrumentalities along the upper apron 19 which perform the additional operations. Obviously, this is objectionable as it will result in defective envelopes

having improper folds, creases or wrinkles in certain of the flap portions thereof. Due to the fact that the conveyed succession of envelope blanks passes over a heater 17 below the lower apron 13, if the machine is stopped for any reason, a certain length of the envelope blanks in the neighborhood of the heater will have the gummed flap portions thereof become unduly heated and this increases the curling tendency thereof. The improved attachment 21 disposed along the upper apron 19 in advance of the instrumentalities for performing the subsequent operations eliminates the curls which might have been formed in the gummed flap portions of any of the delivered envelope blanks.

The manner in which the overlapping envelope blanks with the gummed flap portions are delivered to the attachment 21 is best shown in Fig. 1. It will be noted that the flap portion 16 of each blank passes below the guide and flattening fingers 53 and these are particularly effective in relation to the end edge portions of the flaps wherein the curling tendency may be most pronounced. Beyond the fingers 53 the blanks are delivered between the revolving breaker roll and the revolving pressure rolls. The pressure rolls carry the gears 51 which mesh with the gear 50 on the driven shaft 30, as previously explained, and the breaker roll 26 is driven through being in frictional contact with the pressure rolls 47. It will be observed from Fig. 6 that the breaker roll 26 projects somewhat above the level of the top apron 19 and hence the blanks are drawn and bent over the projecting portion of said breaker roll while passing through the attachment and the direction of bending is opposite to that of the curling tendency of the blank flaps 16. The pressure rolls, moreover, also engage the blanks and the surfaces of said pressure rolls are formed with fine corrugations which aid in eliminating curling and stiffness from the gummed flaps. As each blank passes through the companion rolls of the attachment 21 it is engaged by the rapidly turning propelling cams 20 and moved to another instrumentality in the machine. Upon leaving the attachment 21 the blanks are in a desired flat ironed condition and the gummed flap portions have been effectively de-curved.

When it is desired to release the pressure rolls 47 from their rolling contact with the breaker roll 26 the handles 36 may be turned so as to engage the high sides of the cams 34 with the rod flanges 33, thereby lifting the rods 32 and bearing blocks 29 from the position of Fig. 7 to the position of Fig. 8. This adjustment will elevate the axis of the cradle shaft 30, thereby raising the cradle 38 and all of the parts carried thereby, including the pressure rolls 47. The adjustment just described may be made at any time to free an envelope blank from between the rolls 47 and 26 and it should also be made prior to another manipulation which is necessary to permit a rocking of the entire cradle 38 and the parts carried thereby from the operative position of Fig. 1 to the inoperative position of Fig. 2.

From a description of the parts previously given it was observed that normally the yielding legs 42 on the lower ends of the cradle plates 39 rest on the lower cradle end flanges 43. After the adjustment to permit slight elevation of the cradle 38 has been made, the legs 42 will be slightly raised from the lower apron portions 43 but would nevertheless interfere with and preclude a rocking of the upper cradle 38 on the

shaft 30. To overcome this the turn bolts 41 are released so as to permit the locking plates 40 to be swung from the full line positions of Fig. 3 to the dotted line positions in the same figure, disengaging the upper edges of the end plates 39. Then, said end plates 39 may be shifted upwardly vertically, with enlarged slots 64 permitting such movements. The end plates 39 are also formed with narrow guide slots 65 and adjustable screws 66 are accommodated therein, the latter projecting outwardly from the ends of the cradle. Having released the end plates 39 the same may be shifted upwardly to the position shown in Fig. 9, whereupon the entire upper cradle 38 may be rocked on the shaft 30 from the position of Fig. 1 to the position of Fig. 2. During this movement the swinging arm 62 and shiftable slack take-up sprocket 61 permit the slight re-location of the chain 59 and sprocket 60.

The movement of the upper cradle 38 from the position of Fig. 1 to the position of Fig. 2 is necessary in order to expose the bottom face of the cradle and the pressure rolls 41 disposed therein. If a change is made in the size of the blanks being run in the machine it becomes desirable to change the pressure rolls 41 so as to insert in the cradle longer or shorter pressure rolls, depending on the length of the flaps of the envelope blanks being run. As previously described, the journal frames 46 may be slid on the shaft 30 to permit disengagement of the reduced ends of the pressure rolls and the removal thereof. Upon the insertion of substitute pressure rolls of the desired length, the journal frames 44 are adjusted so that the ends of the pressure rolls may be properly engaged. Also, the driving gear 53 on the shaft 30 may be moved longitudinally to align it with the gears 51 fast on the pressure rolls. Obviously the adjustment of the frames 44 is in accordance with the length of the substituted pressure rolls 41. As the journal frames 44 carry the guide fingers 53 said fingers will be disposed properly at the end portions of the rolls, regardless of the length of the rolls utilized.

From the foregoing description it will be seen that the improved attachment may be applied to a standard envelope folding and gumming machine with a minimum of modification and additions. It functions efficiently and automatically to overcome and eliminate curls and crinkles in gummed envelope flaps. The attachment provides for adjustments and interchangeability of parts to adapt it to blanks of various sizes. The invention is furthermore of simple and novel construction and is well adapted for the purposes set forth.

What is claimed as the invention is:

1. In an envelope machine including an apron and a conveyor for moving a succession of envelope blanks along the apron to operation performing mechanisms, there being a transverse slot in said apron in advance of said mechanisms, a breaker roll revolvably mounted below the apron transversely thereof and projecting into said slot, a cradle rockingly mounted across the apron over the breaker roll and a blank de-curling roller revolvably and removably mounted in said cradle and having its periphery normally in contact with the breaker roll and in the path of blanks moved by said conveyor to engage and roll the same.

2. In an envelope machine including an apron and a conveyor for moving a succession of envelope blanks along the apron to operation performing mechanisms, a cradle rockingly mounted across the apron and in advance of said mech-

anisms, manually operated means carried by the cradle for latching it against rocking, and a blank de-curling roller revolvably and removably mounted in said cradle in the path of blanks moved by said conveyor to engage and roll the same.

3. In an envelope machine including an apron and a conveyor for moving a succession of envelope blanks along the apron to operation performing mechanisms, there being a transverse slot in said apron in advance of said mechanisms, a breaker roll revolvably mounted below the apron transversely thereof and partially projecting through said apron slot, a frame mounted above said apron over the slot, and a pressure roll revolvably mounted in said frame and having its periphery normally in contact with the breaker roll, the crevice between said engaging rolls being in the path of blanks moved by the conveyor whereby the blanks are fed between the rolls and flattened thereby.

4. In an envelope machine including an apron and a conveyor for moving a succession of envelope blanks along the apron to operation performing mechanisms, there being a transverse slot in said apron in advance of said mechanisms, an elongated breaker roll revolvably mounted below the apron transversely thereof and partially projecting through said apron slot, a hollow cradle adjustably mounted above said apron over the slot, separated and longitudinally adjustable journal frames within the cradle, and a revoluble pressure roll within the cradle and having its end portions removably engaged in said adjustable journal frames, the periphery of the pressure roll normally being in contact with the projecting portion of said breaker roll with said contacting roll portions in the path of blanks moved along the apron to iron and flatten the same.

5. In an envelope machine including an apron and a conveyor for moving a succession of envelope blanks along the apron to operation performing mechanisms, there being a transverse slot in said apron in advance of said mechanisms, an elongated breaker roll revolvably mounted below the apron transversely thereof and partially projecting through said apron slot, a hollow cradle adjustably mounted above said apron over the slot, separated and longitudinally adjustable journal frames within the cradle, and a pair of similar revoluble pressure rolls within the cradle and having their axes in the same horizontal plane with their end portions removably engaged in said adjustable journal frames, the projecting peripheral portion of said breaker roll being in rolling contact with peripheral portions of both pressure rolls and in the path of blanks moved along the apron and between the contacting rolls to iron and flatten the blanks.

6. In an envelope machine including an apron and a conveyor for moving a succession of envelope blanks along the apron to operation performing mechanisms, there being a slot in said apron in advance of said mechanisms, an elongated breaker roll revolvably mounted below the apron transversely thereof and partially projecting through said apron slot, a hollow cradle vertically shiftable and rockingly mounted across the apron over said slot, separated and longitudinally adjustable journal frames within the cradle, manually operated latch means engaging the cradle to hold it against undesired vertical and rocking movements, and a revoluble pressure roll within the cradle and having its end portions removably engaged in said adjustable journal

frames, the periphery of the pressure roll normally being in contact with the projecting portion of said breaker roll with said contacting roll portions in the path of blanks moved along the apron to iron and flatten the same.

7. In an envelope machine including an apron and a conveyor for moving a succession of envelope blanks along the apron to operation performing mechanisms, there being a transverse slot in said apron in advance of said mechanisms, an elongated breaker roll revolvably mounted below the apron transversely thereof and partially projecting through said apron slot, a hollow cradle vertically adjustably and rockingly mounted across the apron over said slot, separated and longitudinally adjustable journal frames within the cradle, manually operated latch means engaging the cradle for holding it against undesired vertical and rocking movements, a pair of relatively short revolvble pressure rolls within the cradle and having their axes in the same horizontal plane with the roll end portions removably

engaged in said adjustable journal frames, the projecting portion of the breaker roll normally being in rolling contact with peripheral portions of both of said pressure rolls with contacting portions of the rolls in the path of blanks moved along the apron and between the rolls to iron and flatten the blanks, angled guide fingers carried by said adjustable journal frames and projecting forwardly of the cradle spacedly over the apron, and means for revolving the pressure rolls.

8. In an envelope machine including an apron and a conveyor for moving a succession of envelope blanks along the apron to operation performing mechanisms, a cradle rockingly mounted across the apron and in advance of said mechanisms, means for latching the cradle against rocking, and a blank de-curling roller revolvably mounted in said cradle in the path of blanks moved by said conveyor to engage and roll the same.

ELIJAH G. VALLIER.
